ROLLING MILL CONVEYOR CONTROL SYSTEMS

Bruce E. Frankenfield, Chicago, and Arthur E. Miller, North Riverside, Ill., assignors to Western Electric Company, Incorporated, New York, N.Y., a corporation of New York

Application February 25, 1954, Serial No. 412,424

8 Claims. (Cl. 80—43)

This invention relates to rolling mill conveyor systems, and more particularly to billet-dispatching systems for rolling mills.

In the operation of metal rolling plants provided with a furnace, a roughing mill, an intermediate mill, a finishing mill, a conveyor for advancing billets from the furnace to the mill and a pusher for pushing billets from the furnace onto the conveyor, the billets are sometimes separated between the intermediate mill and the finishing mill in such a manner that alternate billets go through one series of passes of the finishing mill and the other billets go through another series of passes in the finishing mill. In the past, there has been no apparatus for automatically dispatching billets to the roughing mill so spaced that alternate billets are spaced a minimum safe distance apart and substantially no farther apart.

An object of the invention is to provide new and improved rolling mill conveyor systems.

Another object of the invention is to provide new and improved billet-dispatching systems for rolling mills.

A further object of the invention is to provide a billet-dispatching system wherein billets are fed automatically to a rolling mill as the mill needs the billets, the length of each billet to be fed to the mill is measured and the feeding of subsequent billets to the mill is controlled by the lengths of preceding billets.

In a conveyor system illustrating certain features of the invention, billets are dispatched automatically to a roughing mill and an intermediate mill, through which the billets travel seriatim, after which alternate billets travel through one series of finishing passes and the other billets travel through a second series of finishing passes. Before each billet reaches the finishing passes, its length is measured and causes the second succeeding billet to be dispatched to the roughing mill in accordance with that length so that the billets in each series of finishing passes are spaced apart precisely.

A dispatching system for a rolling mill forming a more specific embodiment of the invention may include a continuously operable delivery conveyor for feeding billets to a roughing mill, a furnace, a dispatch conveyor for feeding billets from the furnace to the delivery conveyor and a pusher for pushing billets from the furnace to the dispatch conveyor. The billets are advanced automatically through the roughing mill and an intermediate mill, and are sent alternately to two series of passes of a finishing mill. A photoelectric detecting device stops each billet at the delivery end of the dispatch conveyor, and a second photoelectric detector actuated by a partially rolled billet going therewith and positioned in the intermediate mill actuates the dispatch conveyor to feed a billet from the delivery end thereof to the delivery conveyor when the preceding billet is at a predetermined point in the intermediate mill, and also actuates the pusher to feed another billet to the dispatch conveyor, which moves the latter billet to the temperature measuring device and stops it there. Measuring means located in the intermediate mill measures each billet, and delays the dispatch of the second succeeding billet in accordance with the length of the billet being measured.

The measuring means is so constructed and arranged that the dispatch of each billet to the roughing mill is not delayed by the length of any non-alternate preceding billet.

A complete understanding of the invention may be obtained from the following detailed description of a rolling mill conveyor system forming a specific embodiment thereof, when read in conjunction with the appended drawings, in which

10 Fig. 1 is a schematic, top plan view of an apparatus forming one embodiment of the invention;

Fig. 2 is a view of a portion of a control circuit of the apparatus shown in Fig. 1;

15 Fig. 3 is a view of another portion of the control circuit, the top thereof fitting to the bottom of Fig. 2;

Fig. 4 is a view of the remaining portion of the control circuit, the top thereof fitting to the bottom of Fig. 3; and

Fig. 5 is a schematic view of the apparatus.

Referring now in detail to the drawings, there is shown 20 in Fig. 1 an apparatus for dispatching billets 11 to a mill, dividing alternate billets in two paths and spacing the billets in each path a minimum distance apart regardless of variations in the lengths of the billets. This apparatus includes a pusher 10 of a well-known type for pushing billets 11 of copper into and through a furnace 12, which heats the billets to a suitable temperature for rolling.

25 When the pusher is actuated, it pushes one billet into the furnace and pushes a heated billet out of the furnace onto a dispatch conveyor 15, which moves the heated billet endwise toward a continuously running delivery conveyor 16. As the billet nears the end of the dispatch conveyor 15, it breaks a beam of light from a projector 17 to a photoelectric cell 18 of a well-known type, which is responsive to blue light only, which, of course, is present in white light but not in red light from a heated billet, and the cell 18 causes the conveyor 15 to coast to a stop as the billet reaches a position clearing the beam of light at the end of the conveyor 15.

30 The billet later is fed from the dispatch conveyor 15 to the delivery conveyor 16, and the conveyor 16 feeds the billet through a first pass 32 of a roughing mill 33. The billet drops from the first pass to a guideway 34, and the light therefrom impinges on a photoelectric cell 35 to actuate a pusher 36 to feed the billet through a second pass 37, which rolls the reduced billet and feeds it around a reversing guide 38 to a third pass 39. The third pass 39 advances the billet therethrough onto a tilting shelf 40, and the billet actuates a photoelectric cell 41 to tip the shelf 40 to drop the billet onto a conveyor 42, which feeds the elongated billet back through a fourth pass 43 of an intermediate mill 46 to a guide 44. If the billet actuating the cell 41 is somewhat greater than minimum length, it actuates a photoelectric cell 56 simultaneously with the cell 41, and if the billet is near a maximum length, it actuates a photoelectric cell 57 simultaneously with its actuation of the cell 41. Thus, the cells 41, 56 and 57 measure the billets as short, intermediate and long, and delay the dispatch of secondly succeeding billets in accordance with that measurement, as will be brought out hereinbelow.

45 The guide 44 reverses the billet back to a fifth pass 45, which advances and reduces the billet to rod form and feeds it along a guide 47 to a pivotal selector guide 48. The guide 48 may be held by a pneumatic piston 49, either in a position guiding the reduced billet to a pass 50 or a pass 51 of a finishing mill 52. The passes 50 and 51 feed to passes 53 and 54, respectively, which advance the further reduced rods to subsequent passes 55, the increased length of the billets requiring two passes to keep up with the roughing mill 33 and the intermediate mill 46.

55 As the billet moves from the fifth pass 45 along the guide 47, light therefrom actuates a photoelectric cell 60,

which, after a predetermined delay proportional to the length of the preceding billet, starts the pusher 10 and the dispatch conveyor 15. The conveyor 15 then feeds another billet to the continuously running delivery conveyor 16, and the pusher 10 pushes another heated billet out of the furnace 12 onto the conveyor 15, which feeds it to the light-responsive tube 18 which stops the billet at the end of the conveyor 15.

To automatically feed the billets 11 (Fig. 1) through the furnace 12 to and through the rolling mill, switches 79, 80 and 81 (Figs. 2 and 4) are closed. The switch 80 supplies power to conductors 82 and 83 from a powerline. The projector 17 is energized to actuate, through the photoelectric cell 18, a photoelectric relay 90 of a well-known type to keep open contacts 91, which are open when there is no power on the relay 90 and also when the cell 18 receives white light, but are closed when the beam from the projector 17 is cut off from the cell 18. The switch 79 is set closed and a momentary switch 94 is held closed to actuate relays 95 and 96 to close contacts 97 and 98 in a powerline 99 to energize a motor 100 driving the dispatch conveyor 15 and a motor 101 actuating the pusher 10 (Fig. 1). The pusher 10 pushes the first heated billet from the furnace 12 onto the dispatch conveyor 15, and the switch 94 (Fig. 4) is held closed manually as the first billet travels past the photoelectric cell 18 to the delivery conveyor 16 (Fig. 1), which is running continuously and feeds the billet to the first pass.

The pusher 10 and the dispatch conveyor 15 then advance a second billet, and as it passes the cell 18, the cell 18 is darkened to actuate the relay 90 to close the contacts 91 while the billet is going past the cell 18, and the switch 94 is released to stop the billet at the end of the conveyor 15. Momentary closing of the contacts 91 actuate a relay 110 (Fig. 4), which locks itself in through holding contacts 111 and contacts 112 of a conveyor actuating relay 113 and closes contacts 135. When the switch 80 was closed, a relay 116 pulled up through contacts 117, locks itself in through holding contacts 118 and closes contacts 119 so that, when the starting switch 81 was closed momentarily, a relay 120 was actuated. The relay 120 closed holding contacts 121 and contacts 122 and 123 to lock itself in and actuate a relay 124 and a time delay relay 125. The relay 124 opens contacts 126 and closes contacts 127, 128 and 129. Closing of the contacts 135 by the relay 110 actuated a relay 136 to close contacts 137 and open contacts 138 and 288. The opening of contacts 288 deenergizes the relay 120 to open the contacts 121, 122 and 123. By this time, the time delay relay 125 has been timed out to open contacts 141 to drop out the relay 124 to open the contacts 128 and 129 so that closing of the contacts 137 merely sets up the circuit to the relay 113, which includes holding contacts 142 and contacts 143 for actuating the motors 100 and 101.

When the first billet, which is advanced through the roughing and intermediate mills at a predetermined rate of speed, is advanced through the third pass 39 (Fig. 1), light therefrom impinges on the cell 41 as the entire length of the billet goes therewith. The cell 41 actuates a conventional photoelectric relay 144 (Fig. 2) to close contacts 145 concurrently with the illumination of the cell 41 so that a relay 146 is actuated concurrently with this illumination. The relay 146 immediately closes contacts 153, 154, 155, and 156, and opens contacts 158. The contacts 156 actuate a relay 161 to close contacts 162, 163 and 164 and open contacts 165 to drop out a return solenoid 166 actuating a cylinder (not shown) to hold up the shelf. The closing of the contacts 164 actuates a tilting solenoid 171 to tilt the shelf to drop the billet being rolled when the tail end of the billet clears the cell 41 to drop out the relay 146 and reclose the contacts 158. As the shelf tilts to discharge the billet it opens a limit switch 286 to deenergize the relay 161,

whereupon contacts 164 open and contacts 165 close. The opening of contacts 164 deenergizes the tilting solenoid 171, and the closing of contacts 165 energize the return solenoid 166 to return the shelf to normal position.

If the billet is short in length so that it is not as long as the distance between the cells 41 and 56, the relay 144 is deenergized before a relay 181, actuatable by the cell 56 (Fig. 3), is actuated so that the contacts 154 of the relay 146 are not closed simultaneously with contacts 182 of the relay 181 so that a relay 183 is not energized. However, if the billet is longer than the short length fixed by the distance between the cells 41 and 56, the cell 41 maintains the relays 144 and 146 closed while the cell 56 actuates the relay 181 to close the contacts 182, and this actuates the relay 183 to close contacts 184 and 185, the contacts 184 being holding contacts for the relay 183. The contacts 185 set up a circuit to a timer 187, and, when the billet now at the third pass later goes through the fifth pass 45, it actuates the photoelectric cell 60 to actuate a photoelectric relay 192 to actuate a relay 191 by closing contacts 193. The relay 191, while actuated, closes contacts 194, 195, 196 and 197. Closing of the contacts 196 starts a timer 199, which, after a delay of a minimum period of time desired for the dispatching to the roughing mill of the billet next succeeding the billet at the fifth pass, closes contacts 198 to actuate the relay 120 to close the contacts 122 to actuate the relay 124 which actuates the relay 113 to start the dispatch conveyor motor 100 and the pusher motor 101, and this billet will be just a minimum safe distance behind the billet preceding it through the mill, the billet at the fifth pass, the timer 199 being set for such conditions.

However, assuming the billet at the fifth pass to be of a medium length and to have actuated the cells 41 and 56 simultaneously, thereby actuating the relay 183 and setting up the timer 187. Then, when the billet goes to the fifth pass and actuates the relay 192, the timer 187 immediately is started and opens contacts 201 and holds the contacts 201 open until it times out. When the billet reaches the fifth pass and actuates the relay 191 to close the contacts 196, the timer 199 is started through a circuit including contacts 202 of a timer 203, contacts 204 of a time delay relay 205 and contacts 206 of a relay 207, which is energized on alternate billets and is deenergized on the other billets by a ratchet relay 211.

The ratchet relay, upon energization, closes contacts 212, leaves the contacts 212 closed as it is deenergized, then on the next energization opens the contacts and leaves the contacts open on deenergization. Then, as the next billet dispatched from the conveyor 15 to the mill moves through the third pass, it actuates the cells 41, 56 and 57 according to its length, and assuming it has actuated neither the cell 56 nor the cell 57 simultaneously with the actuation of the cell 41, the relay 207, being closed by the contacts 212, opens contacts 206, 214 and 215 and closes contacts 216, 217 and 218 so that as this next succeeding billet moves to the fifth pass and actuates the relays 192 and 191 to close the contacts 196, the timer 199 is not energized due to the contacts 201 being held open by the timer 187. Then, as the timer 187 times out, the contacts 201 reclose to actuate the timer 199 through the contacts 196, contacts 221 of a timer 222 and the contacts 218, and the billet resting on the delivery end of the conveyor 15 is automatically conveyed to the conveyor 16, which starts it through the mill.

Whenever the timer 199 is actuated to dispatch a billet through the mill, it also opens contacts 231 to break holding circuits to relays 183 and 232, the relay 232 being actuated through contacts 233 of a relay 235 and having holding contacts 234. This drops out the relays 183 and 232 to open contacts 185 and 239. The opening of contacts 185 and 239 deenergizes the timers 187, 203, 205 and 222 to reset them for timing the next billet to pass through the mill. Whenever a billet is going through

the third pass, it illuminates the photoelectric cell 41 to actuate the relays 144, 146, 161 and 211. The ratchet relay 211 is actuated by each billet coming through the third pass and holds the contacts 212 closed on actuation by every second billet until the next succeeding billet comes through the third pass, and keeps the contacts 212 open on actuation by other billets so that the relay 207 is held energized on actuation by every second billet and is held deenergized on actuation by the other billets. When the relay 207 is held energized, it sets up circuits to the time delay relays 203 and 205 for energization by billets long enough to at least simultaneously actuate the cells 41 and 56, and prevents starting of the timers 187 and 222 at this time. On deenergization of the relay 207, it sets up circuits to the timers 187 and 222 for energization by billets long enough to actuate at least the cell 56 concurrently with the cell 41, and breaks the energizing circuits to the timers 203 and 205. Thus, the timers 187 and 222 are subject to actuation by the billets alternate to one another going through the third pass, and the timers 203 and 205 are subject to actuation by the other billets spaced between these alternate billets, provided, of course, the actuating billets for the relays 203 and 205 are sufficiently long to actuate them.

Whenever the relay 207 is deenergized as a billet goes through the third pass, the relays 183 and the contact 184 are locked in if the billet is of medium length or long, respectively. If the relay 207 is energized so that the contacts 218 to the timer 199 are closed as that billet subsequently goes through the fifth pass and calls the timer 199 for the dispatch of another billet from the conveyor 15, this call is effected through the contacts 206 of the relay 207. Thus, the relays 187 and 222 have no effect on the dispatch of the next succeeding billet to the one to which the relays 187 and 222 have just been actuable by. Similarly on the next billet going through the third pass 39, the relay 207 is energized so that the timers 203 and 205 are subject to actuation by this billet, and when this billet goes through the fifth pass 45, the contacts 218 are closed so that, if one of the timers 187 and 222 had been energized, that timer controls the actuation of the timer 199 for the dispatch of the next billet from the conveyor 15. Thus, each billet dispatched by the immediately preceding billet is dispatched as close as possible to the secondly preceding billet without regard to the length of billets alternate with the billet to be dispatched. The timers 187 and 222 are controlled only by the billets going through the same finishing passes as the billet to be dispatched, and the timers 203 and 205 are controlled only by the billets going through the other finishing passes.

A ratchet relay 261 is actuated on each actuation of the relay 191 by a billet going through the fifth pass 45, and alternately keeps contacts 262 open and closed and contacts 263 closed and open. Thus, a solenoid 264 for actuating a valve to throw the guide 48 to the right is actuated alternately with a solenoid 265 operable to actuate the valve to throw the guide 48 to the left.

A manually operable switch 271 is provided for actuating a relay 272 to close contacts 273, 274 and open contacts 275 and 276 to hold the shelf 40 tilted. A relay 281 is operable by a momentary switch 282 to hold contacts 283 and 284 open and contacts 285 closed to actuate the return solenoid 166 to prevent tipping of the shelf 40 while the switch 282 is actuated. The relay 136 is provided with contacts 288 for resetting the relay 120 whenever the relay 113 is actuated to start the conveyor motor 100 and pusher motor 101. By dropping out the relay 120, the circuit to the relay 124 is broken to drop out this latter relay, which cancels the call for the billet that is being dispatched by dropping out the relay 116.

Operation

Assuming the mills 33, 46 and 52 and the conveyor 16 to be running continuously and the switch 80 to be closed,

an operator closes the switch 81 momentarily to actuate sequentially the relays 120, 124, 113 and 95 and 96 to start the pusher motor 101 and the dispatch conveyor motor 100. The pusher 10 pushes a billet onto the dispatch conveyor 15, which advances it to the end thereof, and as the billet momentarily breaks the beam of light from the projector 17 to the cell 18, it actuates the photoelectric relay 90 to actuate the relay 110 which locks in through contacts 111 and actuates the relay 136. The relay 136 then closes the contacts 137 and opens contacts 138. Actuation of the relay 136 opens the contacts 288 to drop out the relay 120, and opening of the contacts 138 occurs before the closing of the contacts 137 to drop out the relay 113 to stop the motors 100 and 101, and the billet comes to a rest at the end of the dispatch conveyor 15. The operator then closes the switch 81 momentarily again to actuate the relays 120, 124 and 113 through the contacts 137 to again start the motors 101 and 100, which feed the billet off the end of the dispatch conveyor to the delivery conveyor 16 and bring another billet from the furnace to the end of the dispatch conveyor, at which time the second billet darkens the photoelectric cell 18 to stop the motors 100 and 101 by dropping out the relays 136 and 113. The relay 120 is dropped out by momentary energization of the relays 136 to break the circuit to the relay 124 which also drops out. As the first billet goes through the third pass, it actuates the photoelectric cell 41 to actuate the relays 144 and 146 simultaneously therewith. If the billet is shorter than medium length it does not actuate either of the cells 56 and 57 simultaneously with the actuation of the cell 41 so that none of the circuits to the timers 187, 203, 205 and 222 is set up. That is, neither the relay 232 nor the relay 183 is actuated and locked in by the shorter billet going through the third pass. If the first billet going through the third pass is of medium length so that it actuates the cells 41 and 56, simultaneously, the relays 146 and 181 are actuated simultaneously and actuate the relay 183 which locks itself in and closes the contacts 185 in the actuating circuits of the timers 187 and 205. If the billet is longer than medium length, it actuates the cells 41 and 57 simultaneously to simultaneously actuate the relays 146 and 235 thereby closing contacts 153 and 233 simultaneously to momentarily energize the relay 232 which locks itself in through holding contacts 234. After the first billet travels from the third pass to the fifth pass, it goes through the fifth pass to actuate the cell 60 to actuate the relays 192 and 191 successively to close the contacts 194, 195 and 196, and since none of the timers 187, 203, 205 and 222 have been actuated prior to the first billet, the contacts 201, 221, 202 and 204 are all closed so that the timer 199 is actuated immediately. Then after a predetermined, minimum delay, the timer 199 opens the contacts 117 and closes contacts 198 to the relay 120. This predetermined relay is brought about by the fact that the timer 199 is a well-known type which must be energized for a predetermined length of time before it actuates any contacts. When the timer 199 times out (ends its timing cycle) it opens contacts 117 and closes contacts 198. This closes holding contacts 121 and also closes contacts 122 to actuate the relay 124 which locks itself in thereby closing the contacts 128 and 129. Assuming the second billet to have arrived at the dispatch end of the dispatch conveyor 15 so that the relay 136 is energized, the relay 113 is energized when the contacts 128 are closed by the relay 124, and the motors 100 and 101 are started to send the second billet to the mill and bring a third billet to the delivery end of the dispatch conveyor 15.

As the first billet goes through the fifth pass and actuates the relays 192 and 191 so that the contacts 194

and 195 are closed, if the first billet was of medium length and had actuated the cells 41 and 56 simultaneously going through the third pass, the relay 183 having locked in through contacts 184 and 231, closing of the contacts 194 actuates either the timer 187 or the timer 205 depending on whether the relay 207 is in an energized condition or deenergized condition. Since the relay 183 remains locked in, the contacts 185 remain closed, even though the billet has cleared the cell 56 and the contacts 182 are now open. Assuming that the relay 207 is in a deenergized condition, the timer 187 is started by the closing of the contacts 194, and, as it is energized, it opens the contacts 201 until it times out. It will be seen, of course, that the timer 187 opening its contacts 201 has no effect on the dispatch of the second billet inasmuch as the relay 207 is deenergized to hold contacts 218 open and contacts 206 closed. If the relay 232 had been locked in by the first billet being long to actuate the cells 41 and 57 simultaneously, the closure of the contacts 195 actuates the timer 222, which interposes a longer delay to the actuation of the timer 199 by the second billet than would the timer 187 so that the third billet would be spaced a sufficient minimum distance from the first billet.

As the second billet goes through the third pass and actuates the photoelectric cell 41, the photoelectric relay 144 is actuated to actuate the relays 146, 161 and 211 sequentially. The relay 211 changes the condition of the contacts 212 from open to closed until the cell 41 is again actuated. Closing of the contacts 212 actuates the relay 207 to open contacts 214 and 215 to the timers 187 and 222, and also opens contacts 206 in the actuating circuit of the timer 199. The relay 207 also closes the contacts 216 and 217 to set up the circuits to the timers 205 and 203, respectively, for actuation by the second billet if that billet is greater than a short length billet. The relay 207 also closes the contacts 218 in the energizing circuit of the timer 199 in series with the contacts 201 and 221 of the timers 187 and 222. Consequently, assuming that the first billet has actuated one of the timers 187 and 222 when the second billet goes through the fifth pass to cause the contacts 196 to be closed, the timer 199 is not actuated until the contacts 201 close in the case of a medium length billet or until both the contacts 201 and 221 close in the case of a long billet.

The first billet having cleared the cell 60 as the second billet goes through the third pass, the second billet sets up the timers 205 and 203 if it is of long length, or the timer 205 only if of medium length. Then, when the second billet actuates the cell 60, the timers 205 and 203 are started, and immediately open contacts 204 and 202 until they time out, which occurs at a time sufficiently after the second billet has left the fifth pass that the fourth billet will not be dispatched until just a minimum safe distance is present between the second and fourth billets. Thus, it will be seen that the timers 187 and 222 are actuatable for every second, or even-numbered, billet, and the timers 205 and 203 are operable alternately with the timers 187 and 222 for the other, or odd-numbered, billets, and each of these timers operates independently of the previous operation of the timers operable alternately therewith so that the lengths of billets odd in the order of dispatch do not interfere with those even in the order of dispatch or vice versa.

The above-described apparatus dispatches each alternate set of billets (the odd-numbered billets) one after another as closely together as is possible without jamming one set of finishing passes of the finishing mill, and also dispatches the other set of billets (the even-numbered billets) in the same manner with respect to the other series of finishing passes in the mill. As a consequence, both series of finishing passes in the mill are operated at maximum capacity.

Certain features of the above-described apparatus are

disclosed and claimed in copending application Serial No. 328,656 for "Conveyor Systems" filed December 30, 1952, now Patent No. 2,790,530 issued Apr. 30, 1957, by J. F. Stoltz and copending application Serial No. 412,616, for "Rolling Mill Conveyor Systems" filed February 25, 1954, by B. E. Frankenfield.

It is to be understood that the above-described arrangements are simply illustrative of the application of the principles of the invention. Numerous other arrangements may be readily devised by those skilled in the art which will embody the principles of the invention and fall within the spirit and scope thereof.

What is claimed is:

1. In a conveyor system for a mill including a dispatch conveyor for delivering a billet to the mill, means for driving the dispatch conveyor, a billet detector positioned at a predetermined point along the dispatch conveyor for stopping the dispatch conveyor, a second billet detector positioned in the mill and actuating means operable by the second billet detector for starting the driving means to start the dispatch conveyor to deliver a billet thereon to the mill, the improvement comprising a timer, a pair of photoelectric relay means located between the detectors and spaced apart a predetermined distance for detecting any billet longer than a predetermined length, means responsive to simultaneous actuation of the photoelectric relay means for actuating the timer, and a circuit operable by the timer for delaying action of the actuating means by the second billet detector.
2. In a mill including a first conveyor section, a second conveyor section, a rolling mill positioned beyond the second conveyor section, means for driving the first conveyor section to deliver a billet to the second conveyor section, means for driving the second conveyor section continuously to convey the billet away from the first conveyor section to the rolling mill, means operable by a billet on the first conveyor section for stopping a billet at a pre-determined point on the first conveyor section, and means operable by a billet at a predetermined point in the rolling mill for actuating the first conveyor section driving means to start the first conveyor section to deliver a billet from the predetermined point on said first conveyor section to the second conveyor section, the improvement comprising means for detecting any billet longer than a predetermined length in the mill prior to the arrival thereof at said point therein, and means for delaying the operation of the actuating means after actuation thereof by a billet in accordance with the length of the last-mentioned billet.
3. A rolling mill conveyor system, which comprises a series of roughing rolls, a first series of finishing rolls, a second series of finishing rolls, means for feeding a first billet from the roughing rolls to the first series of finishing rolls and a second billet to the second series of finishing rolls, means for dispatching billets one at a time to the roughing rolls, means for detecting each billet longer than a predetermined length as it goes through the roughing mill, actuating means located beyond the detecting means and responsive to each billet for actuating the dispatching means to dispatch the next billet, a first timer means, a second timer means, means responsive to the detecting means for actuating the first timer means whenever the first billet of a predetermined length is detected, means responsive to the detecting means for actuating the second timer means whenever the second billet of said predetermined length is detected, means for operatively connecting the first timer means and the actuating means to delay the dispatching means when the second billet actuates the actuating means, and means for operatively connecting the second timer means and the actuating means to delay the dispatching means when the first billet actuates the actuating means.
4. A rolling mill, which comprises a series of roughing rolls, a first series of finishing rolls, a second series of finishing rolls, means for feeding a first billet of a series

from the roughing rolls to the first series of finishing rolls and a second billet to the second series of finishing rolls, means for dispatching billets one at a time to the roughing rolls, means for detecting each billet as it goes through the roughing mill, actuating means located beyond the detecting means and responsive to each billet for actuating the dispatching means to dispatch the next billet, a first timer means, a second timer means, means responsive to the detecting means for starting the first timer means the first billet of a predetermined length is detected, means responsive to the detecting means for starting the second timer means when the second billet of said predetermined length is detected, circuit means for operatively connecting the first timer means and the actuating means to delay the dispatching means when the second billet actuates the actuating means and the first timer means has been actuated and disconnecting the first timer means and the actuating means while the first billet operates the actuating means, and circuit means for operatively connecting the second timer means and the actuating mean to delay the dispatching means when the first billet actuates the actuating means and the second timer means has been actuated and disconnecting the second timer means and the actuating means while the second billet actuates the actuating means.

5. A rolling mill, which comprises a series of roughing rolls, a first series of finishing rolls, a second series of finishing rolls, means for feeding a first billet of a series from the roughing rolls to the first series of finishing rolls and a second billet to the second series of finishing rolls, means for dispatching billets one at a time to the roughing rolls, detecting means responsive to a billet at least of a predetermined length as it goes through the roughing mill, actuating means located beyond the detecting means and responsive to each billet for actuating the dispatching means to dispatch the next billet, a first timer means, a second timer means, means responsive to the detecting means for starting the first timer means when the first billet of at least said predetermined length is detected, means responsive to the detecting means for starting the second timer means when the second billet of at least said predetermined length is detected, means for operatively connecting the first timer means and the actuating means to delay the dispatching means when the second billet actuates the actuating means and the first timer means has been started and disconnecting the first timer means and the actuating means while the first billet actuates the actuating means, and means for operatively connecting the second timer means and the actuating means to delay the dispatching means when the first billet actuates the actuating means and the second timer means has been started and disconnecting the second timer means and the actuating means while the second billet actuates the actuating means.

6. In a rolling mill including a first series of rolls, means for guiding a billet automatically through the series of rolls, a second series of rolls, a third series of rolls, means for dispatching billets one at a time to the first series of rolls, and means for guiding automatically a first billet in order of dispatch to the second series of rolls and a second billet in order of dispatch to the third series of rolls, the improvement comprising means for detecting the length of each billet as it is moved through the first series of rolls, actuating means positioned adjacent to the path of the billets at a point beyond the detecting means and operable by each billet for actuating the dispatching means, a first timer means operable by the actuating means for preventing operation of the dispatching means for a predetermined period of time after actuation by the actuating means, a second timer means, a third timer means, relay means responsive to the detecting means for setting up the second timer means for starting by the first billet longer than a predetermined length, a second relay means responsive to the detecting means for setting up the third timer

means for starting by the second billet longer than said predetermined length, and memory circuit means for starting the first timer means as the second timer means times out and the actuating means is actuated by the second billet and starting the first timer means as the third timer means times out and the actuating means is actuated by the first billet.

7. In a rolling mill including a first series of rolls, means for guiding a billet automatically through the 10 series of rolls, a second series of rolls, a third series of rolls, means for dispatching billets one at a time to the first series of rolls, and means for guiding automatically a first billet in order of dispatch to the second series of rolls and a second billet in order of dispatch to the third series of rolls, the improvement comprising a pair of photoelectric means positioned a predetermined distance apart along the path of the billets in the first series of rolls for detecting the length of each billet as it is moved through the first series of rolls, photoelectric actuating 15 means positioned adjacent to the path of the billets at a point beyond the photoelectric detecting means and operable by each billet for actuating the dispatching means, a first timer means operable by the photoelectric actuating means for preventing operation of the dispatching 20 means for a predetermined period of time after actuation by the actuating means, a second timer means, a third timer means, relay means responsive to simultaneous actuation of the pair of photoelectric detecting means for setting up the second timer means for starting by the first billet longer than said predetermined distance, a second relay means responsive to simultaneous actuation of the pair of photoelectric detecting means for setting up the third timer means for starting by the second billet longer than said predetermined distance, circuit means for starting 25 the first timer means as the second timer means times out and the photoelectric actuating means is actuated by the second billet and starting the first timer means as the third timer means times out and the photoelectric actuating means is actuated by the first billet.

8. In a rolling mill having a first series of rolls, means for guiding a billet through the first series of rolls, a second series of rolls, means for dispatching billets one at a time to the first series of rolls, and means for guiding the billets from the first series of rolls to the second series 30 of rolls, a system for controlling the dispatching means comprising first photoelectric means positioned adjacent to the path of the billet leaving the first series of rolls, second photoelectric means positioned adjacent to said path and spaced from said first photoelectric means a predetermined distance, third photoelectric means positioned adjacent to said path and spaced from the first photoelectric means a distance greater than said predetermined distance, a timer for actuating the dispatching means, fourth photoelectric means positioned adjacent 35 to the path of the billet leaving the second series of rolls for actuating the timer to operate the dispatching means, first timing means responsive to simultaneous actuation of the first and second photoelectric means by a billet for delaying actuation of the timer for a predetermined period, and second timing means responsive to simultaneous 40 actuation of said first and third photoelectric means for delaying actuation of the timer for a period greater than said predetermined period.
